DESIGN FOR A COMBINED BASE AND PEDESTAL FOR TABLE LAMPS

Jane Higgins, Riverside, R. I., assignor to Electrical Testing Laboratories, New York, N. Y., a corporation of New York

Application August 11, 1938, Serial No. 79,240

Term of patent 3½ years

To all whom it may concern:

Be it known that I, Jane Higgins, a citizen of the United States of America and a resident of Riverside, in the county of Providence and State of Rhode Island, have invented a new, original, and ornamental Design for a Combined Base and Pedestal for Table Lamps, of which the following is a specification, reference being had to the accompanying drawing, forming a part thereof.

Figure 1 is a side elevation of a combined base and pedestal for table lamps, showing my new design.

Figure 2 is a top plan view thereof.

I claim:

The ornamental design for a combined base and pedestal for table lamps, as shown.

JANE HIGGINS.
